FLUID HEATER

Charles Bliss, Ardsley, N. Y., assignor to Foster Wheeler Corporation, New York, N. Y., a corporation of New York

Application April 3, 1952, Serial No. 280,346

8 Claims. (Cl. 122—356)

1

This invention relates to fluid heaters and more particularly to tubular heaters for heating fluids.

In various processes wherein fluid is heated in a tubular heater by the passage of gases of combustion in heat exchange relationship therewith in a furnace, it is highly desirable that the gases of combustion be evenly distributed throughout the furnace, not only to evenly heat the fluid flowing through the tubular members but to prevent heat burning out of a portion or portions of said members. Usually, in such heaters, gases of combustion pass to the heater flue through a gas outlet opening or openings along one side or one end of the furnace and generally adjacent the bottom thereof. While gases of combustion may be distributed more or less evenly in portions of the furnace, all of the gases from throughout the entire furnace will so flow to the gas outlet opening that all of said gases will pass in heat exchange relationship with tubular members adjacent the gas outlet opening or openings causing such tubes to overheat or to burn out.

The present invention provides a tubular heater in which gases flowing to a furnace gas outlet opening are uniformly withdrawn from the furnace.

In the heater of the present invention wherein tubular members extend longitudinally of the furnace therein, usually along the opposite sides, roof and in spaced relationship to the bottom thereof and wherein a gas outlet opening or a plurality of gas outlet openings are disposed adjacent the bottom and along one side of the furnace in longitudinally spaced relationship to one another, passages through which gases of combustion flow from the furnace to the gas outlet opening are provided, which passages extend transversely of the furnace below the tubular members adjacent the furnace bottom, said passages having a plurality of openings therein which are substantially equally spaced laterally of one another transversely of the furnace, the passages are so constructed and arranged that gases entering an opening thereafter flow to the gas outlet opening or openings of the furnace out of heat exchange relationship with the tubular members in the furnace.

The invention will be understood from the following description when considered in connection with the accompanying drawing forming a part thereof and in which:

Fig. 1 is a transverse vertical sectional view of a heater embodying the invention; and

2

Fig. 2 is a longitudinal vertical sectional view of the lower portion of the heater illustrated in Fig. 1 taken on the line 2—2 of Fig. 1.

Like characters of reference refer to the same parts throughout the several views.

Referring to the drawing, the heater has a setting including vertical side walls 10 and 11, sloping side walls 12 and 13, end walls 14 and 15, a roof 16 and a bottom 17. Suitable framework designated generally at 18 supports the wall and roof of the setting. The walls of the setting enclose a furnace 19 which is fired, as shown, by two fuel burners 20 and 21 located in the lower central portion of end wall 14.

Vertical side walls 10 and 11 have horizontally extending tubular members 22 and 23 respectively supported adjacent thereto by tube supports 24. The sloping side walls 12 and 13 have similar tubular members 25 and 26 respectively hung adjacent thereto by supports 27 and tubes 28 below roof 16 are supported by hangers 29. Tubular members 30 extend horizontally and longitudinally of the furnace in spaced relationship to the bottom thereof and in substantially the same horizontal plane. The tubes adjacent the side walls, roof and bottom of the furnace are connected by return bend portions which are disposed within the heater, as shown in Fig. 2. Any other form of tube connections may be utilized, however, the connections may be disposed outside of the end walls if desired. Tubular members 22, 23, 25, 26 and 28 are heated principally by radiation from the products of combustion produced by the burners 20 and 21, while tubular members 30 are heated principally by convection heat exchange relationship with said gases passing to furnace gas outlet openings 31 which are disposed, as shown, at the bottom of wall 24 at a lower elevation than the tubes 30. Gas outlet openings 31 are laterally spaced from one another longitudinally of the furnace at substantially the same level and are connected to a flue, not shown, through conduit 32.

In the heater of the present invention, gases of combustion are uniformly withdrawn from the bottom of the furnace by providing a plurality of baffles extending transversely of the furnace 19 below the bottom tubes 30. Each of the baffles are at a different level and are so supported as to provide passages beneath the baffles which passages communicate with the gas outlet openings 31 and also to provide inlet openings for said passages between adjacent baffles. As shown, a plurality of baffles 33 are positioned at a level closely adjacent tubes 30, said baffles extending

longitudinally of the furnace a distance substantially equal to the length of gas outlet openings 31 and transversely of furnace 19 a minor distance of the width of the furnace. A baffle 33 is positioned adjacent each gas outlet opening 31 at a level substantially even with the top of openings 31 and in spaced relationship with wall 11. Baffles 33 are supported on a plurality of tile supports 34 which are laterally spaced from one another to form gas passages 35 therebetween. Other baffles 36 are positioned at a lower level than baffles 33 and are of substantially the same length and width as baffles 33. Baffles 36 are supported on tiles 37 which, like tiles 34, are laterally spaced from one another to form passages 38 therebetween. Gas inlet openings 45 in communication with outlet openings 31 are formed between the inner side of wall 11 and the adjacent side edge of baffles 33 while gas inlet openings 39 to passages 35 are formed between baffles 33 and 36. Baffles 40 are disposed at a lower level than baffles 36 and are of substantially the same width and length as baffles 33 and 36. Tiles 41, similar to tiles 34 and 37, support baffles 40, said tiles being laterally spaced from one another longitudinally of baffles 40 so as to form gas passages 42 therebetween. Gas inlet openings 43 which communicate with passages 38 are formed between baffles 36 and 40, while further gas inlet openings 44 are formed between the baffles 40 and bottom 17 of the heater which last-mentioned gas openings are in communication with passages 42. The tile supports 34, 37 and 41 are positioned in alignment with one another so that passages 42, 38 and 35 communicate with one another and form a continuous flow path transversely of the furnace to the furnace gas outlet openings 31.

In operation, gases of combustion from the furnace 19, after flowing in radiant heat exchange relationship with tubular members 22, 23, 25, 26 and 28, pass downwardly in said furnace, the gases from the area of the furnace directly above baffle 33 pass in heat exchange relationship with tubular members 30 directly above said baffle and flow outwardly of the furnace through gas inlet openings 45 into gas outlet openings 31. Combustion gases from the area of the furnace directly above baffle 36 in flowing downwardly pass in heat exchange relationship with tubes 39 to enter gas inlet openings 39 and passages 35 between tiles 34 and beneath baffle 33. Gases passing downwardly and in heat exchange relationship with tubular members 30 in the area of the furnace directly above baffle 40, flowing outwardly of the furnace through gas inlet openings 43 of passages 38 between tiles 37 and beneath baffle 36, while gases in the area of the furnace above the space between the inner surface of wall 10 and the side edge of baffle 40 adjacent said inner surface enter gas passages 42 between tiles 41 through gas inlet openings 44. In this manner, gases flowing into gas inlet openings 44 pass through gas passages 42 into gas passages 38 below baffle 36 wherein these gases, together with the gases entering inlet openings 43, flow through passages 38 into passages 35. These gases together with gases passing into passages 35 through gas inlet openings 39 flow into gas outlet openings 31 together with the gases passing to said gas outlet openings through inlet openings 45. In this manner, gases are uniformly withdrawn from furnace 19 so that substantially the same volume of gases pass in heat exchange relationship with each of the tubular members 30.

Changes may be made in the form, location and relative arrangement of the several parts of the heater herein disclosed without departing from the principles of the invention. Accordingly, the invention is not to be limited excepting by the scope of the appended claims.

What is claimed is:

1. In fluid heating apparatus, a setting having opposite side walls, opposite end walls, a roof and a bottom forming therebetween a furnace chamber, a plurality of generally horizontally extending tubular members arranged along at least one of said walls, a plurality of generally horizontally extending floor tubular members in spaced relationship with said bottom of the setting, said floor tubular members being laterally spaced from one another, firing means for said furnace disposed above the floor tubular members, said furnace having gas outlet means extending along one wall of the furnace below the floor tubular members, said gas outlet means comprising passage forming means providing a passage extending from a gas outlet opening in said one wall to a point in said furnace chamber adjacent but in spaced relationship with the wall opposite said one wall, the passage forming means having a plurality of baffles providing a top for said passage, said baffles positioned in vertically spaced horizontal planes below said floor tubular members, the upper most baffle nearest said floor tubular members being adjacent said one wall, the other baffles being disposed in successive lower horizontal planes, each of successive baffles extending inwardly of the furnace chamber from a point in substantial alignment with the innermost edge of the baffle next above to a point in substantial alignment with the edge nearest said wall of the baffle next below, thereby providing a plurality of gas inlet openings at a plurality of different elevations below the floor tubular members and at a plurality of points spaced laterally of said one wall and each other toward the opposite wall.
2. The apparatus of claim 1 wherein the gas outlet means comprises a plurality of openings spaced from one another laterally along one wall of the furnace.

3. The apparatus of claim 1 wherein the passage forming means comprises a plurality of gas passages below the floor tubular members, each passage leading to one of said plurality of openings.

4. In fluid heating apparatus, a setting having opposite side walls, extending longitudinally of the furnace, opposite end walls, a roof and a bottom, forming therebetween a furnace chamber, a plurality of generally horizontally extending tubular members arranged along said side walls, a plurality of generally horizontally extending floor tubular members in spaced relationship with said bottom of the setting, said floor tubular members being laterally spaced from one another and extending longitudinally of the furnace, firing means for said furnace disposed above the floor tubular members in one end wall of the setting so as to direct a stream of gases of combustion in a generally horizontal direction toward the opposite end of the furnace, said furnace having gas outlet means extending along one side wall of the furnace below the floor tubular members, said gas outlet means comprising passage forming means extending from a gas outlet opening in said one side wall at substantially right angles thereto to a point in said furnace chamber adjacent to but in spaced relationship with the side wall opposite said one side wall, the passage

forming means having a plurality of baffles providing a top for said passage, said baffles positioned in vertically spaced horizontal planes below said floor tubular members, the uppermost baffle nearest said floor tubular members being adjacent said one side wall, the other baffles being disposed in successive lower horizontal planes, each of successive baffles extending inwardly of the furnace chamber from a point in substantial alignment with the innermost edge of the baffle next above to a point in substantial alignment with the edge nearest said side wall of the baffle next below, thereby providing a plurality of gas inlet openings at a plurality of different elevations below the floor tubular members and at a plurality of points spaced laterally of said one side wall and each other toward the opposite side wall.

5. The apparatus of claim 4 wherein the gas outlet means comprises a plurality of openings spaced laterally from one another longitudinally along one side wall of the furnace.

6. The apparatus of claim 4 wherein the passage forming means comprises a plurality of laterally spaced gas passages extending transversely of the furnace below said floor tubular members, each passage leading to one of said plurality of openings.

7. In fluid heating apparatus, a setting having opposite side walls extending longitudinally of the furnace, opposite end walls, a roof and a bottom forming therebetween a furnace chamber, each side wall having a vertically extending portion and a vertically and inwardly inclined portion above the vertically extending portion and connecting with the roof of the furnace, a plurality of generally horizontally extending tubular members arranged along each of said walls and roof of the furnace, a plurality of generally horizontally extending floor tubular members in spaced relationship with said bottom of the setting, said floor tubular members being laterally spaced from one another and extending longitudinally of the furnace, firing means for said furnace disposed above the floor tubular members in one end wall of the setting intermediate the roof and floor tubular members and so as to direct a

stream of gases of combustion in a generally horizontal direction toward the opposite end of the furnace, said furnace having gas outlet means extending along one side wall of the furnace below the floor tubular members, said gas outlet means comprising passage forming means extending from a gas outlet opening in said one side wall of said wall at substantially right angles thereto to a point in said furnace chamber adjacent to but in spaced relationship with the side wall opposite said one side wall, the passage forming means having a plurality of baffles providing a top for said passage, said baffles positioned in vertically spaced horizontal planes below said floor tubular members, the uppermost baffle nearest said floor tubular members being adjacent said one side wall, the other baffles being disposed in successive lower horizontal planes, each of successive baffles extending inwardly of the furnace chamber from a point in substantial alignment with the innermost edge of the baffle next above to a point in substantial alignment with the edge nearest said side wall of the baffle next below, thereby providing a plurality of gas inlet openings at a plurality of different elevations below the floor tubular members and at a plurality of points spaced laterally of said one side wall and each other toward the opposite side wall.

8. The apparatus of claim 7 wherein the gas outlet means comprises a plurality of openings spaced from one another longitudinally along one side wall of the furnace and wherein the passage forming means comprises a plurality of laterally spaced gas passages extending transversely of the furnace below the floor tubular members, each passage leading to one of said plurality of openings.
